UNITED STATES PATENT OFFICE

2,614,732

MOISTUREPROOF SALT SHAKER

Julius Pararra, Bridgeport, Conn., assignor to
 Pararra-Lefer, Incorporated, Bridgeport, Conn.,
 a corporation of Connecticut

Application June 23, 1948, Serial No. 34,719

2 Claims. (Cl. 222—511)

1

This invention relates to condiment holders, particularly to a salt shaker, and has for an object to provide a simple and effective means for automatically sealing such a device so as to make it moisture proof and prevent absorption of moisture by the salt in the holder when not in use.

Another object is to provide a simple construction which may be easily operated to release the salt or similar material when desired to shake it from the container.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a section through the device showing it in the normal closed or sealed position;

Fig. 2 is a partial side elevation and partial section of the device and also showing the method of use;

Fig. 3 is a top plan view;

Fig. 4 is a section substantially on line 4—4 of Fig. 2, and

Fig. 5 is a side or elevational view of the closure device.

The device comprises the usual glass body or bottle 10 forming a container for the granular material, such as salt 11, and of course this may be of any desired shape. At its upper end it is provided with a reduced neck portion 12 which is threaded as indicated at 13 to receive a similarly threaded cap 14 with a fibre or rubber washer 15 between the upper end of the neck and a shoulder 16 to seal the container when the cap is in place. The cap may also be of any suitable shape, but is preferably tapered at its upper portion as indicated at 17, and it may be made of any suitable material, such, for example, as metal, glass or plastic. This cap is open at its upper end at 18, and has a transverse partition 19 below its upper end provided with a central opening 20. It also has any desired number of openings 21 around this opening 20 for passage of the salt.

The closure comprises a rubber or similar member 22 preferably in the form of a disc provided on its under side with a resilient shank 23 provided with an enlarged head 24. When in position on the cap the shank passes through the opening 20 with the retaining head 24 at the under side of the partition 19. This head 24 is

5 tapered, as indicated, so that it may be passed through the opening 20 from the top, and has a transverse shoulder 25 to engage the under side of the partition 19 to hold the cap in place. 10 Normally, before applying the closure to the cap the shank 23 is shorter than the distance from the top of the cap to the under side of the partition 19, so that in position the shank 23 is stretched, as indicated in Figs. 1 and 2, and the dotted lines in Fig. 5. Therefore, in placing the cap in position the shank 23 is stretched from the short position shown in full lines in Fig. 5 to the dotted line position, so that its head 24 may be passed through the opening 20 in the partition 19 to bring this head to the underside of this partition, as shown in Fig. 1. Therefore, in this position as the shank is stretched, and as it tends to shorten due to its resiliency, it will automatically hold the disc 22 of the closure on the top 15 of the cap to seal the outlet opening 18, and thus maintain the device moisture proof and prevent the salt from absorbing moisture from the air. The disc is larger than the top of the cap so as to overhang it.

20 25 In use, the operator merely places a thumb or finger on the top of the closure at one side edge, as indicated for example in Fig. 2, and presses downwardly on this edge. This tips the disc or closure as indicated and removes it from one side of the opening 18, so that the operator by then tipping or turning the container to an upside-down position, can shake the salt from the container, it passing through the openings 21 and the top opening 18. As soon as the closure 22 is 30 released, the stretched resilient neck 23 automatically swings it back into closed position to seal the opening 18 in the cap. Should it be found that the best rubber composition for the closure 22 is not stiff or rigid enough to maintain its shape, a thin disc 26 of metal, plastic, fiber or other suitable more rigid material than the rubber may be molded within this closure to give it greater stiffness or rigidity.

40 45 It will be evident from the above that this is a very simple device involving a minimum number of parts, that when not in use the container is automatically sealed to prevent absorption of moisture by the salt so that it is maintained in a dry or free flowing condition, but that it may be readily operated for dispensing this material; also that after removing the cap the device may be readily cleaned.

Having thus set forth the nature of my invention, I claim:

1. A shaker for salt and similar material in-

cluding a container with a relatively small discharge opening at the top surrounded by a relatively narrow rim, a support inwardly of the discharge opening permitting passage of the material to the discharge opening, a closure for the discharge opening on the outer side thereof and including a resilient rubber under side resting on the rim, a resilient elastic shank connected to and extending from the under side of the closure through the discharge opening and connecting the closure with the support, said shank being under stress so that it automatically retains the under side of the closure against the rim over the discharge opening, and said closure including a portion extending outwardly beyond the rim of the discharge opening so as to overhang this rim and which overhang is free to move downwardly by pressure on its top surface so that it forms a finger grip which on downward pressure rocks the shank and closure toward one side of the rim of the discharge opening as a pivot to shift the opposite side of the closure away from said rim to permit passage of the material from the container.

2. A shaker for salt and similar material including a container with a discharge opening at the top surrounded by a narrow rim, a support inwardly of the discharge opening, a closure and attached shank for the discharge opening including a resilient yieldable under side resting on said rim on the outer side of the discharge opening, said closure including a portion extending outwardly beyond the rim so as to overhang this rim and form a finger grip free to move downwardly by pressure on its top surface to tip the closure about the rim on one side of the discharge opening as a pivot and shift the opposite portion of

the closure outwardly away from the rim and the discharge opening to permit passage of the material from the container, a resilient elastic shank passing through the discharge opening connected at its opposite ends to the closure and the support, and said shank being under stress so that it automatically returns the closure to the closed position and retains it against the rim to close the discharge opening when pressure on the finger grip is released.
